US0D1098636S

(12) **United States Design Patent** (10) **Patent No.:** **US D1,098,636 S**
(45) **Date of Patent:** **** Oct. 14, 2025**

(54) **ANTI BARKING DEVICE**

(71) Applicant: **Shenzhen Xuanyu Xing Technology Co., Ltd.**, Shenzhen (CN)

(72) Inventor: **Lirong Dai**, Shenzhen (CN)

(73) Assignee: **Shenzhen Xuanyu Xing Technology Co., Ltd.**, Shenzhen (CN)

(**) Term: **15 Years**

(21) Appl. No.: **29/909,768**

(22) Filed: **Aug. 10, 2023**

(51) LOC (15) Cl. **30-99**

(52) U.S. Cl.

USPC **D30/199**

Primary Examiner — Christian P. Mclean

(57) **CLAIM**

The ornamental design for an anti barking device as shown and described.

DESCRIPTION

FIG. 1 is a front, right, top perspective view of an anti barking device showing my new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 3; and,

FIG. 11 is an enlarged view of the encircled area 11 of FIG. 4.

The broken lines shown on the drawings depict portions of the anti barking device that form no part of the claimed design. The dot-dash broken lines surrounding the enlargements in FIGS. 1, 3, 4 and 9–11 are for the purpose of annotating the enlarged views only, and form no part of the claimed design.

1 Claim, 11 Drawing Sheets
